UNITED STATES PATENT OFFICE

SAMUEL McDONALD, OF LOUISVILLE, KENTUCKY.

STAFF-HOLDER.

1,155,589.

Specification of Letters Patent.

Patented Oct. 5, 1915.

Application filed February 10, 1913, Serial No. 747,454. Renewed August 16, 1915. Serial No. 45,847.

To all whom it may concern:

Be it known that I, SAMUEL McDONALD, a citizen of the United States, residing at Louisville, in the county of Jefferson and 5 State of Kentucky, have invented certain new and useful Improvements in Staff-Holders; and I do declare the following to be a full, clear, and exact description of the invention, such as will enable others skilled 10 in the art to which it appertains to make and use the same.

This invention relates to supports, and more especially to staff holders adapted for supporting an upright rod or staff; and the 15 object of the same is to form a support of this character capable of holding flag staffs, usually of bamboo, such as those employed on golf courses. The staffs of direction flags so used vary in sizes, and sometimes there 20 will be a plurality of sizes used on one golf course, so that it becomes necessary to have a plurality of staff holders especially constructed to receive and support the respective staffs. This is avoided by the use of 25 my improved holder, which is adapted for quick adjustment to any staff within limits.

The following specification sets forth details of construction, as shown in the drawings wherein—

30 Figure 1 is a perspective view of this device complete. Fig. 2 is a central vertical section showing the staff in dotted lines. Fig. 3 is an enlarged cross section on the line 3—3 of Fig. 2.

35 This device is by preference made entirely of metal, properly treated to prevent rust, and its size will be that which is especially adapted to the particular use to which it is put. While I prefer to employ it for supporting the staffs of direction flags on golf courses, the invention is of course capable of 40 many other uses, and is especially designed to support upright tubular members of varying sizes.

45 Coming now to the details of the present invention, the numeral 1 designates a pin, preferably of steel and preferably sharpened at its lower end as at 2 although this is not essential; but however said lower end is entered in or supported upon the ground, I prefer that the upper end be pointed as at 3.

The numeral 4 designates the upper member or socket as a whole, the same comprising a collar 5 at its lower end which is secured around the pin 1 and preferably brazed or soldered thereto as at 6, and three

or more upwardly projecting arms 7 which diverge from each other just above the collar as at 8 and then extend substantially or nearly straight upward and are slightly curved in cross section to constitute jaws 9. This socket-member is by preference also made of steel, being brazed at 6 onto the pin 1 as above suggested if said pin is of steel, but if the pin be of some other material any appropriate fastening means between the two members might be employed. As shown the upper pointed end of the pin 1 projects above the lower diverging portion 8 of the collar and between the yielding arms 4 of 70 the staff holder, whereby the lower end of the latter may be forced downwardly along the length of said holder and upon the pin thus forcing said arms outwardly or from one another, it being understood however, 75 that the clamp 10 is adapted to be adjusted along the arms of the socket to permit said arms to be forced apart when the staff is inserted within the clamp. Thus it will be seen that when the staff has been inserted 80 in the socket, as described, the clamp 10 may be adjusted along the length of the yielding arms of the clamp to hold the staff in a rigid position with its lower end securely fixed upon the pin, all of which is 85 due to the construction of the lower diverging yielding portion of the socket upon which the staff is forced. If the parts are named for the functions they perform, the pin member might be called a "base" and 90 its details of structure are capable of wide variation so long as it has the point 3 at its upper end, while the upper member may well be termed a "socket" because it has all the functions of a socket. Any proper or 95 appropriate form of clamp may be employed for drawing the upper ends or jaws 9 of the arms toward each other, the clamp herein illustrated being a slit band having outstanding extremities or ears 11 through 100 which is passed a bolt or screw 12. However, I do not wish to be limited to any specific form of clamp, so long as one is present.

In use this device has its base seated on or pushed into the ground or other support, so that the holder will stand upright as seen in the drawings. The clamp is then loosened and run down on the socket member, and the flag staff F passed into the then 110 wide open jaws and pressed downward until its lower end is centered within the socket

member on the point 3. This will occur automatically and quickly if said staff is of bamboo, which is the usual material employed for the staffs of direction flags on 5 golf courses, but if not of bamboo it will be an easy matter to force a wooden flag staff downward onto the point 3. The clamp 10 is then slipped up on the socket member 4 until the upper extremities or jaw-ends 9 of 10 the arms are borne inward to a sufficient extent to grip the staff F in a manner which will be clear. It is therefore held at two points—at its lower extremity which is centered on the point 3, and at a higher point 15 where it is gripped within the jaws 9. It is my purpose to make the socket member as large as the largest flag staff which it is to receive, and when this staff is inserted therein the clamp 10 must be expanded so 20 that the jaws 9 may open wide or to a position where the arms 7 will stand in parallelism with each other. When any smaller size of staff is inserted its lower extremity will center on the point 3, but the clamp 25 must be tightened up to bring the jaws into contact with the smaller staff. In the form illustrated the clamp is obviously tightened by setting the nut on the bolt 12, but I do not wish to be limited to the use of this 30 form of clamp. Therefore, it will be seen that the use of the point 3 at the upper end of the base member or within the lower end

of the socket member obviates the necessity for any means which would draw the arms together near their lower ends, and hence 35 the provision of but one clamp at the upper ends of said arm is necessary.

What is claimed as new is:

A staff holder comprising a socket consisting of a plurality of yielding arms, a 40 collar forming the lower end of said socket from which the lower diverging ends of the arms of said socket project, a pin secured within the collar forming the lower end of said socket and having a pointed end adapted to project into the socket and above the diverging lower portions of the arms forming said socket, and a collar adjustable upon and along the length of the arms of said socket whereby when a staff is inserted within the socket and forced upon the pointed end of the pin located therein and against the diverging portions of the arms of said socket, said staff will be rigidly held at a space and properly centered before the 45 clamp is adjusted.

In testimony whereof I have hereunto set my hand in presence of two subscribing witnesses.

SAMUEL McDONALD.
